UNITED STATES PATENT OFFICE.

EARL THOMPSON, OF SYRACUSE, NEW YORK.

DESIGN FOR A CHAIR.

48,917.

Specification for Design.

Patented Apr. 18, 1916.

Application filed November 23, 1915. Serial No. 63,125. Term of patent 14 years.

To all whom it may concern:

Be it known that I, EARL THOMPSON, a citizen of the United States, and a resident of the city of Syracuse, county of Onondaga, and State of New York, have invented a new, original, and ornamental Design for Chairs, of which the following is a specification, reference being had to the accompanying drawing, forming part thereof.

The figure is a perspective view of a chair showing my new design.

I claim:

The ornamental design for a chair, as shown.

Signed at New York in the county of New York and State of New York this 8 day of November, A. D. 1915.

EARL THOMPSON.

Witnesses:

ROBERT M. GLUCK,
JUSTIN S. GALLAND.
